UNITED STATES PATENT OFFICE.

CHARLES WALTER WATKINS, OF DORRANCETON, PENNSYLVANIA.

FURNACE-DOOR CONSTRUCTION.

1,183,702.

Specification of Letters Patent. Patented May 16, 1916.

Application filed January 28, 1916. Serial No. 74,800.

To all whom it may concern:

Be it known that I, CHARLES W. WATKINS, a citizen of the United States, residing at Dorranceton, in the county of Luzerne and State of Pennsylvania, have invented new and useful Improvements in Furnace-Door Constructions, of which the following is a specification.

This invention relates to improvements in 10 furnace doors and has particular application to safety door construction especially adapted for use in connection with the furnaces of steam boilers.

In carrying out the present invention, it 15 is my purpose to provide a safety door for steam boiler furnaces which will be constructed in such manner that the door, in the event of the same being opened, will be automatically closed in the event of one of 20 the tubes of the boiler bursting, by the action of the steam in the furnace, thereby preventing the escape of steam and hot gases through the fire door and causing such gases to pass to the outer air through the 25 smoke stack or flue of the furnace.

It is also my purpose to provide a safety door for steam boiler furnaces which may be swung to open and closed positions easily and with a minimum effort on the part of 30 the attendant and which will be automatically held in either of its positions and which will be constructed in such manner that steam escaping from a broken tube or the like into the combustion chamber will 35 act upon the inner surface of the door to hold the latter tightly closed so as to prevent the steam from passing through the door opening and into the fire room.

Another object of my invention is to provide 40 a door of the class described which will embrace the desired features of simplicity, efficiency and durability, which will embody comparatively few parts and these so arranged and correlated as to reduce the possibility 45 of derangement to a minimum, and which may be manufactured and installed at small cost.

With the above and other objects in view, the invention consists in the construction, 50 combination and arrangement of parts hereinafter set forth in and falling within the scope of the claim.

In the accompanying drawings, Figure 1 is a fragmentary front elevation of a steam 55 boiler furnace equipped with a fire door constructed in accordance with the present in-

vention. Fig. 2 is a vertical sectional view through the same. Fig. 3 is a horizontal sectional view therethrough. Fig. 4 is a vertical cross sectional view through the 60 door and the adjacent portion of the furnace. Figs. 5 and 6 are detail views of the invention. Fig. 7 is an enlarged fragmentary sectional view through the door. Fig. 8 is a fragmentary side elevation of the 65 same.

Referring now to the drawings in detail, 70 1 designates the front wall of a steam boiler furnace, such wall being formed with a door opening 2 opening into the fire chamber of 75 the furnace and through which the coal or other fuel may be delivered to the fire chamber. Secured to the front wall of the furnace in alinement with the door opening 2 is a frame 3 of a shape corresponding to the 75 shape of the door opening. In the present instance, the inner end of the frame 3 is formed with an outwardly projecting flange 4 lying in face to face contact with the wall of the furnace around the door opening and 80 passed through the flange 4 and the furnace wall 1 are securing bolts 5 or other fastening devices. The frame 3 projects outwardly from the wall of the furnace a short distance and secured to the respective vertical side 85 portions of the flange 4 and projecting outwardly from such portions are bearing brackets 6 having the outer end portions thereof formed with horizontally alining bearing openings 7 disposed slightly above 90 the horizontal center line of the frame 3. In the present instance, each bearing bracket 6 comprises lower and upper sections 8 and 9, respectively placed edge to edge and 95 formed on the confronting edges of the respective sections are a tongue and groove 10 and 11 designed to interfit so as to hold the sections against relative movement. 12 designates a horizontal pivot rod arranged 100 across the outer edge of the frame 3 and having the ends thereof turned down as at 13 and journaled in the bearing openings 7 in the brackets 6. In this form of my invention the turned down ends of the pivot rod are surrounded by bushings 14 constructed 105 of suitable material and is designed to take the wear.

Fastened upon the horizontal pivot rod 12 in some suitable manner and adapted to close the outer end of the frame 3 is a door 110 15 capable of swinging movement into the frame to open the door opening so that the

fuel may be delivered to the fire chamber of the furnace. The connection between the pivot rod and the door is arranged at a point above the horizontal center line of the door, as clearly illustrated in Figs. 1 and 2 of the drawings, while formed on the upper edge of the door above the pivot rod is a flange 16 adapted to abut the upper edge of the frame 1 and the portions of the side edges of the frame above the pivot rod when the door is in closed position, while formed on the lower edge of the frame and the side edges thereof below the pivot rod is an inwardly extending flange 17 adapted to engage the corresponding edge portions of the door when the door is closed. These flanges coöperate with each other to form a fluid tight connection between the door and the frame so as to prevent the ingress of air to the fire chamber and the discharge of any gas from the fire chamber to the fire room.

The outer ends of the pivot rod 12 project beyond the respective bearing brackets and fastened to these ends are arms 18 arranged at right angles to the rod and adjustably mounted upon the arms 18 are counterweights 19 adapted to counterbalance the door when in open position so as to hold the door in such position against the action of gravity. The outer ends of the arms 18 are connected with the handle bar 20 spanning the space between the arms whereby the door may be swung to open and closed positions.

Normally, the door is held in closed position under the action of gravity and when it is desired to open the door, the arms 18 are swung by means of the handle bar 20, thereby rotating the pivot rod and swinging the lower portion of the door into the frame 3. The counterweights on the arms assist in opening the door and act to hold the door in open position. To close the door the handle bar 20 is operated in the reverse direction and as the arms pass the center of the pivot rod the door drops to closed position under the action of gravity and remains in such position.

Should a boiler tube burst or any other abnormal condition arise in the boiler, or the fire chamber, the gases entering the fire chamber will act upon the door to hold the latter tightly against the flange 17 and hold the flange 16 on the upper portion of the door tightly against the top portion of the frame, thereby preventing the escape of the gas into the fire room and compelling such gas to pass through the smoke stack or flue to the outer atmosphere. In the present instance, the door 15 comprises an outer or front plate 21 and an inner liner 22. The liner 22 is spaced apart from the front plate 21 and the confronting faces of the plate and liner are formed with interfitting lugs 23 and are connected to each other by means

of bolts 24 passed through alining openings in the plate and liner and lugs. These lugs are suitably spaced apart and coact with one another to prevent accidental movement of the liner relatively to the front plate in the event of the bolts wearing. The liner is formed with a number of air holes 25, while formed in the front plate 21 are air openings 26 and pivoted upon the front plate is a wicket 27 movable to cover and uncover the air openings 26.

Formed on the rear side of the liner 22 adjacent to the lower edge thereof is a lug 28 adapted to abut the top wall of the frame in the movement of the door to open position and this lug 28 acts to prevent the door from assuming a horizontal position when swung inwardly. Thus, the door presents a surface to the interior of the fire chamber, when such door is open, upon which steam or other gases may act to automatically swing the door to closed position so as to prevent the escape of gas to the fire room in the event of abnormal conditions arising in the fire chamber.

It will be seen that I have provided a safety door for steam boiler furnaces which may be manufactured and installed at practically the same cost as the ordinary furnace door, while the door may be readily opened and closed and will be automatically closed in the event of an abnormal condition arising in the furnace. This door will be found especially useful on the steam boiler furnaces of seagoing vessels, locomotives, buildings and, in fact, may be used upon any steam boiler furnace.

When my improved safety door is used upon a locomotive boiler furnace, I employ means for holding the door in closed position. In the present instance, I have shown this holding means in the form of a chain 29 having one end fastened to an eye bolt 30 carried by the upper portion of the frame 3 and the other end equipped with a hook 31 adapted to engage the upper portion of the door to hold the door closed.

While I have herein shown and described one preferred form of my invention by way of illustration, I wish it to be understood that I do not limit or confine myself to the precise details of construction herein described and delineated, as modification and variation may be made within the scope of the claim and without departing from the spirit of the invention.

I claim:

In a safety door for steam boiler furnaces, the combination with the front wall of the furnace having a door opening therein, of a frame secured to the front wall of the furnace in alinement with the door opening therein and corresponding in shape to the shape of the door opening and projecting beyond the front wall of the furnace, bearing

brackets disposed at opposite sides of said frame and projecting outwardly beyond the outer edges of the side pieces of the frame, a horizontal pivot rod carried by said brackets and arranged across said frame and disposed at a point above the horizontal center line of the frame, a door secured to said pivot rod, a flange on the upper portion of said door adapted to abut the corresponding edges of said frame, a flange on the outer portion of said frame adapted to be engaged by the corresponding portions of said door and coöperating with the first-named flange to form a fluid-tight connection between the door and the frame, means carried by the inner side of said door and adapted to en-

gage the top wall of said frame in the movement of the door to open position to prevent the door from assuming a horizontal position whereby the door will present a surface to 20 the interior of the furnace against which the gases may act to close the door, and counterbalancing means for said door to hold the latter in open position against the action of gravity.

In testimony whereof I affix my signature in presence of two witnesses.

CHARLES WALTER WATKINS.
